Application May 31, 1943, Serial No. 489,136
In Great Britain July 28, 1942

11 Claims. (Cl. 179—18)

The present invention relates to telephone or like signalling systems and is more particularly applicable to the setting and control of automatic telephone switching apparatus over long lines, which may include speech transmission thermionic repeaters, by means of voice frequency signals which will readily pass through the repeaters.

In voice frequency dialling and signalling systems of this type as hitherto designed, trains of dialled impulses comprising interruptions in a direct current circuit are converted at the sending end of a trunk or toll line into voice frequency form and are re-converted back again at the terminating end into their original direct current form. In these circumstances the problem of impulse distortion due to the reactive effect of the line and its terminations always arises and it is the chief object of the invention to provide a system in which this problem, at least as far as the voice frequency signalling line is concerned, is avoided.

According to one feature of the invention, in a telephone system suitable for long distance automatic working and employing signals of a plurality of voice frequencies for effecting the selective setting of automatic switches over a trunk line, a variable length train of impulses received from a calling party by equipment at the outgoing end of the trunk line is transmitted over the trunk line in the form of a single pulse of substantially constant length comprising one or more voice frequencies the nature of which varies in accordance with the number of impulses in the train.

According to another feature of the invention, in a telephone system suitable for long distance automatic working and employing signals of a plurality of voice frequencies for effecting the selective setting of automatic switches over a trunk line, a pulse comprising a plurality of frequencies is transmitted prior to the selective pulses to prepare the equipment for response thereto.

A further feature of the invention is that in a telephone system suitable for long-distance automatic working and employing signals of a plurality of voice frequencies for effecting the selective setting of automatic switches over a trunk line, each train of impulses received from a calling party by equipment at the outgoing end of the trunk line is transmitted over the trunk line in the form of a code of substantially constant length regardless of the number of impulses in the train and arrangements are provided for

varying the interval between codes representing successive impulse trains dependent on the number of impulses in the preceding train.

The invention will be better understood from the following description of one method of carrying it into effect, reference being had to the accompanying drawings, comprising Figs. 1-8.

Figs. 1-4 when arranged in the manner indicated in Fig. 3a show the circuits of an outgoing manual-to-automatic relay set which connects over a V. F. signalling line with a distant incoming relay set, the circuits of which are shown in Figs. 5-8 which should be arranged in the manner shown in Fig. 7a. The local outgoing and distant incoming relay sets together provide for V. F. signalling and coded impulsing from an outgoing trunk line operator's position of the sleeve controlled type as already employed for "on demand" trunk service.

Before the detailed circuit operations are dealt with, the method of working will be described generally. When the operator plugs into the jack of a free outgoing line equipment, her calling supervisory lamp flickers and a 100 millisecond (m. s.) X voice frequency pulse is sent forward to the distant incoming end to seize the associated selector. The operator now operates the dialling key whereupon the lamp is extinguished and she then dials the required subscriber's number which is received and stored on uni-selectors at the outgoing end. Each train of impulses received is re-transmitted over the line in coded digit form involving up to three of four voice frequencies, hereafter referred to as W, X, Y and Z, and each coded digit transmitted is preceded by a preparatory signal comprising all four frequencies W-Z, which is effective at the distant exchange to prepare the voice frequency receiver thereto to receive the coded digit which follows.

At the distant end each received coded digit has to be converted back to a train of direct current loop impulses to actuate the switching apparatus thereto, and the receiving equipment is so arranged that after a preparatory signal comprising all four frequencies together has been received, the digit code following and consisting of not more than three frequencies W-Z will operate a W, X, Y, Z relay contact pyramid by means of which the code information can be decoded and converted into a marking on a uni-selector for controlling the sending out of a corresponding train of loop impulses.

The second coded digit is transmitted after an interval sufficient to meet the numerical setting

and hunting requirements of the selector and at the terminating end of the line it is decoded as before. Similar remarks apply to the succeeding digits, and when all have been received at the distant end, and when the switching equipment thereat has been set to connect with the required subscriber, the calling operator will receive ringing tone, busy tone, or number unassigned tone to denote the state of the called line. In the meantime, on completing the dialling of the required digits, the operator will have restored the dialling key, and will thus have caused her supervisory lamp to glow. When the called subscriber answers, a Y tone of 200 m. s. length will be sent back to the originating end to extinguish the supervisory lamp and to establish conversational conditions thereat.

Conversation now takes place, and when the calling subscriber clears, 140 m. s. length pulses of Y tone at spacings of 360 m. s. are returned from the incoming end to the originating end and cause the operator's supervisory lamp to glow. When the operator clears by removing the plug from the outgoing jack, an X tone of 1½-2 seconds length is sent forward to the incoming end, followed by a Y tone of 300 m. s. length and the distant equipment is thereupon restored to normal.

Among special arrangements provided according to the present invention to secure efficient operation is the adjustment of the length of the pause between coded digits transmitted over the line in accordance with the setting up and hunting time required by the distant selector switches. In the illustrated embodiment, it is arranged that for the digits 1-5 a predetermined pause is provided which will cover the setting up and hunting requirements of digit 5 where the maximum time is involved, and that for the digits 6-0 this pause is increased to cover the requirements of the greatest digit 0. By providing pauses between transmitted coded digits which will cover the setting up and hunting requirements of the distant switches in turn, it is possible to avoid providing storage facilities for more than one digit at the incoming end of the line as the same storage relays can be repeatedly used for each digit in turn, while the adjustable pause arrangement ensures that this form of digit transmission shall not be unduly extravagant in time.

Considering the operation in detail, when the outgoing operator plugs her cord circuit calling plug into the jack O_{GJ} associated with the outgoing relay set shown in Figs. 1-4, if the cord circuit speaking key is thrown, battery via the cord circuit calling supervisory lamp controlling relay in the operator's position circuit will be extended over the sleeve of the plug and jack to operate relay M by way of its left-hand low resistance winding, whereupon at contacts m₁ it brings up relay MM and at contacts m₂, Fig. 4, it steps switch TS from its home position to position 1. Relay MM in operating, at its contacts m₂, connects a flicker earth source via lead 10 to the left-hand low resistance winding of relay M so that the calling supervisory lamp is caused to glow on each application of earth, while on each disconnection relay M holds on both its windings in series, the total resistance being then such that the supervisory lamp controlling relay in the position sleeve circuit will not hold in series therewith so that the lamp is extinguished. Switch TS in advancing to position 1 brings up relays FXY and CO, Fig. 2, over its wipers and banks TS₁ and TS₂. Relay CO has no particu-

lar function at this time but relay FXY at contacts fxy₁, Fig. 1, connects X frequency to one winding of transformer T₁, the return path being completed over lead RTN. The X frequency is thereupon applied to the outgoing trunk line conductors 14 and 15, whereupon at the voice frequency receiver VFR₂, Fig. 5, associated with the distant incoming relay set, an X frequency responding relay or its equivalent is operated and at contacts x₁ brings up its relief relay XR. Relay XR in operating, at contacts x₁ 3, Fig. 7, brings up relay K, which thereupon at contacts k₁ locks independently of relay XR, at contacts k₂ prepares a circuit for relay AR in readiness for the termination of the X frequency and at contacts k₆, Fig. 8, brings up relay PY which however has no function at this stage.

At the outgoing end relay FXY at contacts fxy₃, Fig. 4, completes a self-driving circuit for switch TS to advance its wipers to position 3, whereupon the circuit of relay FXY is opened at wiper and bank TS₁, Fig. 2, and this relay commences to release slowly. Relay FXY on releasing, at contacts fxy₁, Fig. 1, terminates the sending out of the X frequency, the period of application of which will have been of the order of 100 m. s. as determined by two steps of the switch TS at 20 m. s. per step plus the 60 m. s. release lag of relay FXY. Relay FXY also at contacts fxy₁ reconnects a suitable V. F. line termination via resistance YD and at contacts fxy₂, Fig. 2, brings up relay FC which thereupon locks over its contacts fc₁ to earth via bank and wiper TS₂. Relay FC also at contacts fc₂, Fig. 4, advances the TS switch to position 4 from which it is stepped to position 6 over bank and wiper TS₃ from an interrupted earth source connected to lead 11 and delivering 140 m. s. on, 360 m. s. off, the stepping time therefore being one second.

At the distant incoming end where relay XR has been held operated in response to the X frequency and where relays K and PY are also operated, the cessation of the X frequency results in the release of relay XR, whereupon at contacts x₁ 3, Fig. 7, earth is extended forward over operated contacts k₂ to bring up relay AR. Relay AR in operating, at contacts ar₁, Fig. 6, extends a seizing earth via the winding of relay IR and one winding of the repeating coil RPC₂ over the negative wire to the A relay of the selector switch associated with the incoming relay set. The selector A relay and relay IR operate in series and the former prepares the selector for receiving direct current loop impulses from the incoming relay set, while the latter at contacts ir₁, Fig. 7, brings up relay NN and at contacts ir₂, Fig. 8, holds relay PY independently of relay K. Relay NN has mainly a preparatory function at this stage, but contacts nn₆, Fig. 6, provide a shunt path round contacts ar₁ of relay AR.

No further circuit operations occur at either end of the trunk line until the operator throws her position dialling key, whereupon battery is extended forward from the position over the cord tip and ring conductors and a high resistance is introduced into the sleeve circuit to extinguish the calling supervisory lamp. The battery over the tip conductor brings up relay RR, Fig. 1, and this relay in operating, at contacts rr₁, Fig. 1, brings up relay AM, whereupon at contacts am₁, Fig. 4, earth is extended to operate relay B, Fig. 2. Relay B in operating, at contacts b₂ and b₃, Fig. 1, connects relay AM to the tip and ring conductors so that this relay now holds over its upper winding independently of relay RR,

the circuit of which is disconnected at contacts *b*4 so that it releases after a short interval. At contacts *b*5 the flicker earth circuit is opened and relay KR is introduced into the sleeve circuit but owing to the high resistance which has been included in this circuit in response to the operation of the dialling key, relay KR will not operate though relay M remains held.

The operator now dials the first digit of the required number, and when the dial is moved off-normal, the battery connection to the tip and ring conductors at the operator's position is removed and these conductors are now looped together over the dial impulsing springs so that relay AM is now held energised over both its windings in series. On the first interruption of the impulsing circuit, relay AM in releasing, at contacts *am*1, Fig. 4, extends earth over contacts *b*1 and low resistance winding of relay C, wiper and bank DD2 of the digit distributor switch DD to the magnet DSAM of digit switch DSA, while on the subsequent re-operation of relay A the magnet is de-energised to advance its wipers to position 1. If the digit 5 is dialled, the DSA switch wipers will be advanced to position 5. Relays B and C hold operated during the train and contacts *c*2 energise the magnet DDM of the digit distributor switch DD during this time. On the release of relay C at the end of the train, magnet DDM is de-energised and advances the DD switch wipers to position 1, while at contacts *c*1, Fig. 3, earth is extended via contacts *cna*1 and wiper DSA2 in position 5 to operate relays CNA and CNR in series. Relay CNA in operating, at its contacts *cna*1 locks itself over wiper and bank DSA2 independently of the contacts *c*1, at contacts *cna*2 prepares a further locking circuit for itself, at contacts *cna*3 prepares an operating circuit for relay EP, at contacts *cna*4 prepares the V. F. sending circuit and at contacts *cna*5 prepares a homing circuit for switch DSA. Relay CNR in operating, at contacts *cnr*1 initiates the sending out of the corresponding V. F. coded digit in a manner to be later described.

In response to the second and subsequent dialled digits, the digit distributor switch DD at its wiper and bank DD2 functions to distribute the impulse train to the other digit switches DSB, DSC (not shown) and to digit switch DSD, reception of digits on these switches bringing up the associated relays CNB, CNC and CND, Fig. 3.

Immediately the first dialled impulse train has been completely received as indicated by the operation of relay CNR, sending out of the corresponding V. F. coded digit over trunk line 14, 15 is initiated. On the operation of relay CNR, contacts *cnr*1 step switch SC off-normal, whereupon it operates relay ST by way of both its windings in series with magnet SCM which cannot operate in this circuit. Relay ST thereupon at contacts *st*1 short-circuits its left-hand high resistance winding, whereupon magnet SCM is operated and switch SC self-drives to position 4 where the holding circuit for relay ST is opened and this relay commences to release. During the operated time of relay ST, contacts *st*2—*st*5, Fig. 1, apply all four frequencies W—Z to the trunk line by way of transformer *T*1 to provide the preparatory signal which precedes the transmission of each coded digit, while contacts *st*6, Fig. 2, disable the V. F. receiver VFR1 associated with the outgoing relay set. On the release of relay ST, contacts *st*1, Fig. 3, operate relay S over both its windings and bank and

wiper SC1 in series with magnet SCM and when relay S operates and at its contacts *s*1 short-circuits its left-hand high resistance winding, switch SC will commence to self-drive to position 9. Relay ST in releasing disconnects the four-frequency signalling circuit and relay S in operating, at contacts *s*4, Fig. 1, connects up to line a frequency combination in accordance with the digit dialled as controlled by the DSA switch banks DSA3—DSA6 which connect up with contacts *s*4 over operated contacts *cna*4 and resting contacts *zr*3.

The proposed V. F. digit code is as follows:

15	Digit	Code	Digit	Code
1		W	6	XZ
2		Z	7	YZ
3		WX	8	WXY
4		WY	9	WXZ
5		WZ	0	WYZ

In response to the dialling of digit 5 the DSA switch wipers will have been set to position 5, and in order that in this instance a coded digit comprising frequencies W and Z may be sent out, the leads representing these frequencies will be wired up to contacts 5 on banks DSA3 and DSA6, the contacts 5 on banks DSA4 and DSA5 being left unwired. On the operation of relay S following the release of relay ST, the four prepare frequencies W—Z will therefore be replaced by the two frequencies W and Z.

The sending out of the two frequencies W and Z continues until the switch SC reaches position 9 where the circuit of relay S is opened. In this position during the slow release of relay S, relay ZR operates over its lower high resistance winding in series with magnet SCM which is inoperative owing to the high resistance of relay ZR. Relay ZR thereupon at contacts *zr*1 completes a homing circuit for the digit switch DSA via its upper low resistance winding, contacts *cna*5 and wiper and bank DSA1, at contacts *zr*2 completes a locking circuit for relays CNA and CNR in series independent of bank and wiper DSA2 and at contacts *zr*3, Fig. 1, terminates the sending out of the W and Z frequencies. During the homing of switch DSA, relay ZR is maintained operated over its upper winding and when the switch DSA reaches its home position, relay ZR releases and at contacts *zr*1 completes a homing circuit for switch SC, and at contacts *zr*2 opens the locking circuit for relay CNA. This relay then releases and relay CNR will also release if no further digits have yet been dialled.

If by this time the operator has completed the dialling of the second digit, which will be assumed to be 8, relay CNB will have been operated in series with relay CNR and consequently with relay CNR still held, switch SC on reaching its home position will commence another cycle of operation. Relay ST is again operated and functions in the same manner as before to send the "prepare" pulse and is followed by relay S to send out the code corresponding to digit 8 which is WXY.

The SC switch on advancing to contact 9 terminates the sending out of the W, X and Y frequencies corresponding to digit 8 by operating relay ZR which proceeds to home the DSB switch, the homing circuit extending in this case via the upper low resistance winding of relay ZR, resting contacts *cna*5 and operated contacts *cnb*5 and bank and wiper DSB1. This is followed by the homing of switch SC, whereupon the equipment

will be ready to send out the next received impulse train in coded form.

The interdigital pause is partly determined by the homing time of the digit switch controlling the coded digit which has just been sent out, the time concerned being the homing time from the position to which this switch has been set by dialling plus the homing time of switch SC from position 9. This arrangement provides a suitable interdigital pause for digits up to 5. In the case of digits 6-0 this time would be slightly less and in fact a longer time is required to cover the correct functioning of the switches at the distant end. This is taken care of by arranging to operate a relay EP, Fig. 3, when relay S operates to initiate the sending out of a coded digit of a value from 6-0. For instance when relay S operates to initiate the sending out of the frequencies W, X and Y corresponding to the second dialled digit 8, on the operation of relay S, contacts *s3* complete a circuit to operate relay EP from earthed operated contacts *cnb1*, wiper *DSB2* on contact *8*, operated contacts *cnb3*, normal contacts *cna3*, operated contacts *s3* to battery via the winding of relay EP. In this instance relay CNB will have been operated by way of its right hand winding, the left-hand winding only being used for digits up to 5. Relay EP in operating, at its contacts *ep1* locks itself independently of relay S and at its contacts *ep3* (not shown, but assumed to be located in Fig. 4 and connecting the home contact of bank *DSB1* with the other contacts) prepares for the provision of an extra pause after the second digit 8 concerned, the other contacts *ep2*, *ep4* and *ep5* serving similarly for providing an extra pause if required, after the first, third and fourth digits respectively.

When switch DSB restores to its home position after the sending out of the coded digit 8, since relay EP is operated at this time the switch wipers are again advanced to position 1 from which the switch continues to rotate through another full cycle. During this time relay ZR will be maintained operated and will maintain relays CNB and CNR from earth over contacts *zr2*, *cna2*, *cnb2*, left-hand winding of relay CNB to battery via relay CNR. While switch DSB is stepping to position 6, the holding circuit for relay EP will be opened at bank and wiper *DSB2* and this relay will release during this time so that when switch DSB reaches position 6 relay EP will be unable to re-operate. Hence when the switch DSB reaches the home position on the additional cycle, since relay EP will now be normal, there will be no circuit to step it on from its home position and relay ZR will therefore release. Relay ZR in releasing homes the SC switch and releases relay CNB. The SC switch on reaching its home position waits until the next digit has been received, or, as before described, continues another cycle if this has already been received.

Considering now the reception of the coded V. F. digits at the incoming end, the WXYZ "prepare" signal which precedes each digit operates all four relays WR-ZR, Fig. 5, contacts of which bring up relay CA, Fig. 6. It will be remembered that at this incoming end relays K, PY, AR, IR and NN are operated as a result of the seizure of the trunk line. On the operation of relay XR, relay AR, Fig. 7, is released but without effect, while on the operation of relay CA, contacts *ca1*, Fig. 6, prepare an operating circuit for relay CB

to the earthed contacts *nn5*. On the receipt of the actual coded digit, which consists of three or less frequencies, i. e., the reduction of frequencies W, X, Y and Z to frequencies W and Z in the case of the first digit 5, or the reduction to frequencies W, X and Y in the case of the second digit 8, the short-circuit will be removed from relay CB which now operates. Relay CB in operating, at its contacts *cb4* and *cb1*, Fig. 5, completes holding circuits for relays WR and ZR which are operated in response to the coded digit frequencies W and Z where digit 5 is involved, so that on the cessation of these frequencies, relays WR and ZR will remain held. Other contacts of these relays which are not shown are arranged in a known pyramid formation so as to set up a suitable marking over the fifth of the ten leads 1-0, Fig. 8, to contact *6* of the bank *SS2* of the sender switch SS so as to control the sending out of a number of direct current loop impulses corresponding to the V. F. coded digit 5 concerned.

Relay CB also at contacts *cb5*, Fig. 7, brings up relays P and C. Relay C in operating, at contacts *c1* brings up relays CC and GY and at contacts *c2* and *c3*, Fig. 6, releases relay IR and loops the outgoing negative and positive leads via the impulse sending circuit which involves the motor driven "loop" impulsive contact springs *IMP1*, at present short-circuited by wiper *SS1* in its home position. Relay P in operating locks over its contacts *p1* and at its contacts *p5*, Fig. 8, operates relay CK, contacts *ck2* and *ck3*, Fig. 5, of which serve to terminate the trunk line via resistance *YE* while loop impulses are subsequently transmitted from the incoming relay set. Relay GY has no direct function at this stage but relay CC in operating, at its contacts *cc2*, Fig. 8, connects earth to the motor driven "magnet" impulse springs *IMP2*.

The impulse springs *IMP1* and *IMP2* are operated ten times per second, the former being closed for 33% of the period of each impulse and the latter being closed for the remaining 66% of the period. If on the operation of relay CC the impulse springs *IMP2* are open, or if not, when they next open, relay IG operates and at contacts *ig1* connects these springs to magnet SSM. On the next closure of the springs *IMP2*, magnet SSM is energised and on the next opening, magnet SSM is de-energised and advances the SS wipers to position 1. At this point the loop impulse springs *IMP1* are closed, so that when springs *IMP2* again close to re-energise magnet SSM, springs *IMP1* in opening produce the break portion of the first output impulse. On the next opening of springs *IMP2*, the SS switch wipers are advanced to position 2 while springs *IMP1* now close to terminate the break portion of the first output impulse. During the stepping from position 2 to position 3 the second impulse is sent out and so on until five impulses have been sent out corresponding to the received V. F. coded digit. Wiper *SS2* on reaching position 6 at this time will encounter an earth marking which will be connected thereto over contacts of relays WR and ZR within the known pyramid arrangement. Relay SZ thereupon operates and locks over its contacts *sz1*, while at contacts *sz2* it short-circuits the loop impulse springs *IMP1* to prevent further impulses being sent out to the first selector, and at contacts *sz3* it releases relays CB and CA.

In response to the train of five loop impulses, the first selector is stepped up to level 5 and then proceeds to perform an automatic rotary

hunting operation to find a succeeding selector in the selected group. Relay CB in releasing, at contacts *cb4* and *cb1* releases relays WR and ZR, at contacts *cb5* re-operates relay AR over contacts *ca2* and *yr3* and opens the circuit of relay C, and at contacts *cb6* it releases relay IG, whereupon the SS switch self-drives to its home position, relay SZ remaining locked to bank and wiper SS3 during this time. When switch SS3 reaches its home position, relay SZ releases and re-prepares a circuit for relay CE. On the release of relay C after its slow period, relay CC is released and relay GY commences to release slowly and the repeating coil RPC2 is re-connected to the outgoing negative and positive leads so that relay IR re-operates. Relay CK, Fig. 8, is connected up over lead *i2* to an interrupted earth source which gives one second pulses at four second intervals and therefore slowly pulses but without effect at this stage except under special conditions when busy tone is returned from the selector as described later.

With relays K, PY, NN, P, AR and IR held and with relay CK pulsing, the incoming end is now ready to receive a further set of frequencies corresponding to the next dialled digit 8 which will be transmitted from the outgoing end after the proper pause as determined at this end in the manner already described.

Digit 8 comprising frequencies W, X and Y is now received and as in the case of the frequencies for the code signal 5, it is preceded by all four frequencies W, X, Y and Z to prepare the receiving equipment by operating relay CA. The sending out of the train of eight direct current impulses corresponding to the received code signal now takes place in the manner before described. Similar remarks apply to succeeding coded digits until all the digits transmitted have been received, decoded, and retransmitted in normal loop impulse form to set up the selector train to the required subscriber.

At the outgoing end, where relays M, MM, CO, FC, AM and B are held operated, the operator after dialling the required digits will restore her dialling key, whereupon a comparatively low resistance battery potential is momentarily applied at the operator's position circuit to the sleeve of the calling plug and this battery extends over jack OGJ to bring up relay KR. Relay KR thereupon at contacts *kr2* prepares for called party supervision, at contacts *kr1* removes the battery feed for relay AM which remains held on its upper winding to battery applied to the tip and ring conductors in the position circuit and at contacts *kr3* provides a local locking circuit for relay KR. After the momentary application of resistance battery to the sleeve circuit, the high resistance originally introduced into this circuit on operation of the dialling key is short-circuited, while a short interval later the battery applied to the tip and ring conductors in the position circuit is removed and relay AM releases. On the resultant release of relay B after its slow period, contacts *b5* connect earth over contacts *ct3*, *kr2*, *b5* and *mm2*, and the left-hand low resistance winding of relay M to the sleeve circuit so as again to bring about the lighting of the calling supervisory lamp. This condition persists until the called subscriber answers.

Meanwhile, the selector train at the distant exchange will have connected with the required subscriber and if he is free, the final selector will return the interrupted ringing tone back over the speaking conductors to the incoming relay set,

where it is further slowly interrupted by contacts *ck2* and *ck3* though without any particular purpose in this instance. The tone then extends back to the outgoing relay set where it finds a circuit to the outgoing operator via transformer T1, the single way or so-called "stopper" valve SV and repeating coil RPC1. The primary function of valve SV is to prevent transmission from the cord circuit to the trunk line so as to prevent noise or the like at the outgoing end switching the line echo suppressors against the passage of tones and signals from the distant incoming end.

At the incoming end, during the transmission of ringing tone, relays K, AR, PY, NN, IR and P continue to be held operated, while relay CK continues to be slowly pulsed.

When the called subscriber answers, the line battery feed to the calling side of the final selector circuit is reversed and the battery applied to the positive line operates relay I, while relay IR releases. Relay I in operating, at contacts *i1*, Fig. 7, releases relay K and this relay at contacts *k3* brings up relay GX, while at contacts *k6*, Fig. 8, the circuit of relay PY is opened. During the release time of relay PY relay FY is brought up over contacts *ir2*, *k6* and *py3* and at contacts *fy1* steadily energises relay CK which up to now has been pulsing. Relay PY in releasing opens the circuits of relays FY and CK, and during the release time of these two relays a 200 m. s Y frequency "subscriber answer" signal is sent back to the outgoing end to dim the operator's calling supervisory lamp and to complete the conversational conditions thereof.

At the outgoing end relays M, MM, KR, CO and FC are held operated at this time and the TS switch is in position 6. On receipt of the Y frequency, this extends over transformer T2 into the V. F. receiver VFR1 and brings up a Y relay or its equivalent, contacts *y1* of which bring up relay RS. Relay RS in operating, at contacts *rsl* prepares a circuit for relay RD, and at contacts *rs2* operates relay SA which thereupon at contacts *sa1* brings up relay CT and at contacts *sa2* locks via bank and wiper TS2. Relay CT in operating, at contacts *ct2*, Fig. 1, applies battery via resistance YC to the ring conductor for through supervision purposes in cases where the outgoing operator's position is serving in an intermediate capacity between a calling and a called exchange, at contacts *ct3* disconnects the earth applied to the sleeve circuit so as to extinguish the calling supervisory lamp, and at contacts *ct4* and *ct5* establishes through conversational conditions at the outgoing end. At the conclusion of the Y frequency pulse, relay RS commences to release slowly and during this time relay RD operates and maintains relay CT over contacts *rd1* and *ct1*. When relay RS releases, relay RD slowly releases in turn, relay CT now remaining held to earth via contacts *sa1* and bank and wiper TS1.

Conversation now proceeds between the calling and called parties, relays AR, NN, I, P, and GX being held operated at the incoming end. At its conclusion the called party on hanging up brings about restoration to normal of the line feeding battery potential at the final selector, whereupon relay IR again operates and relay I releases. This results in the transmission of a clearing signal comprising 140 m. s pulses of Y frequency at spacings of 360 m. s. back to the outgoing end to effect the lighting of the outgoing operator's supervisory lamp. Relay I in releasing, at contacts *i2*, Fig. 8, brings up relay CK and this relay at

contacts *ck1* connects up a 140 m. s. on, 360 m. s. off earth source over lead 13 to relay FY, whereupon at contacts *fy2*, Fig. 5, 140 m. s. pulses of Y frequency are returned over the trunk line conductors 14 and 15.

At the outgoing end where relays M, MM, CO, FC, KR, SA and CT are held operated, the first Y pulse brings up relay RS and the first off period brings up relay RD during the slow release period of relay RS and relay DR maintains relay CT. When the next Y pulse arrives, relay RD will not yet have released due to the combined release times of this relay and relay RS being longer than the 360 m. s. off period so that the holding circuit for relay CT which has been previously maintained over contacts *rd1*, *ct1*, *y1*, *st6* and *s5* to earth is now opened at contacts *y1* and relay CT now releases. Relay RS operates on this and subsequent Y frequency pulses and relay RD remains steadily operated since it is energised during the release time of relay RS during each interval and remains held due to its slug during each impulse. On the release of relay CT, the conversational condition at the outgoing end is broken down at contacts *ct4* and *ct5* and at contacts *ct3* earth is extended forward over the sleeve circuit to give the clearing signal to the operator by lighting the calling supervisory lamp. The reason for arranging the circuit to require two Y pulses to give the required control is to prevent simulation of the clearing signal by speech.

On receipt of the clearing signal, the operator will withdraw her calling plug from jack OGJ and relay M thereupon releases, whereupon relay MM commences to release slowly. The other relays SA, CO, FC remain held to bank and wiper TS2, relay CO, on the release of relay MM, maintaining an engaged test battery via resistance YB on the sleeve of jack OGJ. Relay MM also releases relay KR. Relay M at contacts *m2*, Fig. 4, causes the TS switch to advance to position 7 from which earth over contacts *sa4* causes it to self-drive to position 15 where its driving circuit is opened at bank TS4. During this time relay B, Fig. 2, is operated over bank and wiper TS1. When switch TS reaches contact 15, it proceeds to advance onward to position 19 under control of a 140 m. s. on, 360 m. s. off interrupted earth supply connected to lead 11 which extends to magnet TSM via bank and wiper TS3. When position 19 is reached, relay B has its circuit opened and commences to release slowly, while relay FXY is now operated. This operation of relays B and FXY in turn serves to send forward a "clear down" signal comprising a 1½ second pulse of X frequency followed by a 300 m. s. pulse of Y frequency. It will be seen from Fig. 1 that relay B in operating, at contacts *b6* extends X frequency over contacts *mm4*, *st2*, *fy1* and resistance YD to the winding of transformer T1 from whence it extends to line. This circuit is maintained until relay FXY operates and opens the X frequency circuit at contacts *fy1*, the time being determined by the stepping of switch TS from position 7 to position 19. On the operation of relay FXY, contacts *fy1* connect Y frequency to line. On the release of relay B after its slow period, a self-interrupted driving circuit is completed for switch TS at contacts *b8* and the switch thereupon advances its wipers to position 20. The circuit for relay FXY is now broken at bank and wiper TS1 and after the slow release period of this relay, the transmission of the Y frequency to line is terminated. It may be mentioned here that the X frequency pulse will have forced the

line echo suppressors to change round in favour of forward sending from the outgoing end, so that during this time relays RS and RD will have released. On application of the Y frequency at the sending end, relay RS re-operates and on the termination of the Y frequency, relay RD is brought up during the release time of relay RS. During this time the switch TS will have been self-driving from position 19 and when it reaches position 24, it will remain there until both relays RS and RD restore when contacts *rs4* and *rd2* will allow the switch to step on to its home position. In this position relays SA, FC and CO which have been held operated from wiper and bank TS2 are released and the outgoing relay set is ready to deal with further calls.

At the incoming end, the position is that relays AR, NN, P, IR, CK and GX are held operated while relay FY is pulsing. On receipt of the X frequency which will occur during the silent period of the Y clearing signal being sent from the incoming end, relay XR operates and at its contacts *xr3*, Fig. 7, operates relay GY which disconnects the pulsing circuit of relay FY and so terminates the sending of the Y pulses, while at the same contacts the circuit of relay GX is opened so that it commences to release slowly. On the release of relay GX relay CC is operated and the equipment now awaits the Y frequency from the outgoing end. On receipt of this frequency, relay YR is operating, at contacts *yr3* brings up relay CR. This relay at contacts *cr2* operates relay C and at contacts *cr1* locks itself and disconnects relay NN which commences to release slowly. Relay C in operating releases relays IR and AR so that when relay NN releases, the forward holding loop to the selector train is opened and this train now restores to normal. Relay NN in releasing also releases relays P, CC, GY and C and on the release of relays P and CC, relay CR releases. On the termination of the Y frequency, relay YR releases and the incoming equipment is ready for further use.

The primary function of relays GX and GY at the incoming end is to prevent false operation due to components of speech simulating the X and Y signalling frequencies and the arrangements are such that a false X frequency followed by a false Y frequency will be ineffective unless the false X frequency is of at least 300 milli-seconds duration. It will be appreciated that the possibility of a false X frequency of at least 300 milli-seconds immediately followed by a false Y frequency is extremely remote. During conversation the operation of the supervisory relay I will have restored relay K to normal so that if a component of speech during this time simulates the X frequency, relay GX will start to release slowly owing to the operation of relay XR. Only if the component is sufficiently long, i. e., above 300 milli-seconds duration, will relay GX be released and relay CC operated, and the connection will only be released if a false Y signal follows immediately so as to operate relay CR.

Assuming now that the outgoing operator clears in face of number unassigned tone or if the called subscriber fails to answer, in order to be sure of clearing down the distant incoming equipment particularly in face of number unassigned tone which may be applied continuously for 4 seconds, it is arranged that the X frequency of the clear down signal is lengthened to a period of the order of 6 seconds, this frequency being followed by the usual 300 m. s. Y frequency.

On the withdrawal of the plug, relays M, MM

and KR release as before. Relay M in releasing causes the TS switch to advance to position 7, but in this instance since relay SA has not been operated owing to non-receipt of a "subscriber answer" signal, the switch TS will not now self-drive to position 15 as before, but instead will advance step by step from the interrupted earth supply on lead 11 to this position from which it will again advance under control of the same earth supply to position 19 as before. From position 19 the switch moves on to its home position as already described. During the stepping from position 7 to position 19 relay B is operated to send out X frequency as before, but in this instance the increased stepping time of switch TS gives approximately a 6-second period of transmission of X frequency. The 300 m. s. Y frequency then follows in the manner already described.

At the incoming end relays K, AR, NN, PY, P and IR will be in operated condition and relay CK will be being slowly pulsed. The reception of the X frequency results in the operation of relays XR, C, CC and GY in turn. Relay C in operating causes the steady operation of relay CK, releases relay IR and transfers the selector holding loop to wiper and bank SS1. The receipt of the Y frequency brings up relays YR and CR, whereupon relays K, NN, CK, C, CC, PY, P and CR are released and the loop to the selector train is broken. At the termination of the Y frequency, relay YR releases and the incoming equipment is restored to normal.

In case busy tone is returned from the final selector, or a preceding selector, the circuit operations at the outgoing end are the same as described for the number unassigned or ringing tone, but at the incoming end before reception of the clearing signal, relay I will be impulsed from the busy flash battery applied at the selector in addition to the relays held as already mentioned. The first full operation of relay I releases relay K which cannot re-operate and relay K in releasing operates relay GX and opens the slow pulsing circuit for relay CK so that this relay now remains normal. The busy tone now extends through without further interruption from the final selector to the operator, the interruption at the incoming relay set being unnecessary with busy tone as the echo suppressors can readily restore during the silent periods. When the operator subsequently withdraws her plug, the 6-second X, 300 m. s. Y frequency clear down signal is now sent forward as described. At the incoming end relay XR responds to the X frequency and brings in relay GY, while when relay GX releases, relay CC operates. In response to the Y frequency relay YR brings up relay CR which operates relay C and also releases relay NN which disconnects the circuits of relays C, CC, CR, P and GY. The operation of relay C releases relays IR and AR and relays AR and NN initiate the release of the selector train so that on the release of relay YR at the end of the Y frequency, the equipment will be in readiness for further use.

In case the distant incoming relay set is to function in a tandem capacity and where, for example, the first two digits received are required to select an outgoing V. F. trunk to a further exchange, when the tandem selector train has been set up, an outgoing DC/VF relay set of a similar type to that accessible to the distant outgoing operator will be taken into use and a signal, conveniently in the form of a posi-

tive battery applied to the test lead P, will be returned to the tandem incoming relay set to provide a through path from the incoming relay set to the selected tandem outgoing relay set in order to allow the subsequent coded digits to extend straight through to the terminating exchange.

Referring now to Fig. 6, if after the transmission of the appropriate number of trains of 10 loop impulses a positive battery is applied to the test lead P at the tandem outgoing relay set taken into use, relay DCO operates and at its contacts dco1 cuts off any further circuit for relay CB and at the same contacts completes a locking circuit for itself. At this time relays K, PY, AR, NN, IR, and P will be operated and relay CK will be pulsing, while relays CA, CB and C will be normal. When relay DCO operates, at contacts dco2 it opens the circuit of relay K, and on release of this relay contacts k3 connect up relay GX and contacts k5 release relay CK. Thereupon at contacts ck2 and ck3 the incoming trunk conductors 14 and 15 are extended through via repeating coil RPC2 and the tandem selector train to the tandem outgoing relay set taken in use. Hence received coded V. F. signals corresponding to the subsequent digits dialled will extend straight through to the tandem outgoing equipment without having been operative at the incoming equipment since as relay CB cannot be operated, the digits are not stored and no circuit is completed for stepping the switch SS. The coded V. F. signals accordingly extend through the tandem outgoing equipment and out over the second trunk line through to another incoming equipment at the distant end, which will correspond to that already described.

It may be that access is also required to be had to the tandem outgoing relay set from an ordinary direct current selector train in which case the relay set will be required to function in similar manner to that at the originating exchange, that is to say, to convert D. C. dialled impulses to coded V. F. pulses. When such a 40 relay set is seized via a selector train from an incoming V. F. trunk as described above, however, no conversion will be necessary as the digital information will already be in V. F. coded form. To enable the tandem outgoing relay set to meet these two requirements a suitable discriminative method of seizure is utilised, seizure in the former case where conversion is required being characterised by a direct current loop across both legs of the incoming line, while seizure in the latter case where conversion is not required will be characterised by a balanced earth connection on to both legs of the line via the relays I and IR in the tandem incoming relay set concerned.

In the system just described it has been arranged to precede each coded V. F. digit by a preparatory signal comprising all the signalling frequencies in combination. One function of this is to ensure that the line echo suppressor is switched in the right direction in readiness for the following coded digit and so to prevent clipping thereof, and another function is to exercise the incoming voice frequency signal receiver. An advantage of this arrangement is that unless all 60 the frequency responsive relays in the incoming voice frequency receiver function correctly, it will be impossible to send out trains of impulses and hence the sending out of incorrect digits due to partially stored frequency codes is prevented. 70 Further-more if on seizure of a selector by the

incoming equipment, transients of the order of the dialing frequencies are encountered, these might be stored by the incoming voice frequency receiver and sent out in corresponding impulse form. With the illustrated arrangements however, this trouble is avoided since the incoming equipment is not properly responsive until after a "prepare" signal has been received. Though it is possible to avoid trouble due to signal clipping by the echo suppressor by making each coded digit of sufficient duration as to be substantially unaffected thereby, the other troubles which arise when the "prepare" signal is not utilized would still obtain and the arrangement described therefore adds appreciably to the reliability of the system.

What we claim as new and desire to secure by Letters Patent is:

1. In a telephone system, a trunk line, a responsive device, means in the trunk line responsive to different length series of impulses received from a calling party for transmitting over the trunk line to said responsive device single impulses each comprising a plurality of voice frequencies varying in number in accordance with the length of the received series of impulses.

2. In a telephone system, a trunk line terminating in an automatic switch, means associated with said trunk line and responsive to received series of impulses for transmitting to the automatic switch an impulse of substantially constant length including a plurality of alternating currents of different frequencies, the number of frequencies in said single impulse varying in accordance with the number of impulses in said received series.

3. In a telephone system, a trunk line, a plurality of automatic switches accessible thereto, means associated with the trunk line for transmitting an impulse of current thereover comprising a plurality of voice frequencies before each switch is operated and means for then transmitting another impulse comprising a lesser number of said voice frequencies to the switches to operate the same, the number of voice frequencies in the second impulse varying in accordance with the operations required in each of said automatic switches.

4. In a telephone system, automatic switches, a register, means for transmitting series of impulses to said register to variably operate the same, means in the register for simultaneously transmitting a plurality of voice frequencies to operate the switches, each plurality of voice frequencies simultaneously transmitted varying in composition in accordance with the number of impulses in the series registered.

5. In a telephone system as set forth in claim 4 in which there is means in the register for delaying the time of transmission of the voice frequencies corresponding to a series of impulses for a time period varying in accordance with the number of impulses in the series registered.

6. In a telephone system, a register, means in the register responsive to a plurality of received series of impulses for transmitting an impulse of substantially constant length for each series received, regardless of the number of impulses in the series, and means in the register for varying

the time interval between transmitted impulses representing received series of impulses, dependent on the number of impulses in the preceding series.

5 7. In a telephone system, a trunk line, automatic switches, means for simultaneously transmitting a plurality of voice frequencies to said automatic switches to extend a connection over said trunk line and means for transmitting a supervisory signal back over the trunk line after the connection is extended comprising a single one of the voice frequencies used in the operation of the switches.

8. In a telephone system, a trunk line, an automatic switch, a plurality of sources of alternating current of different frequencies, means of connecting one of said sources to said trunk line to seize said switch, means for simultaneously connecting all of said sources to the trunk line to prepare the switch for operation, and means for simultaneously connecting particular combinations of said sources to the trunk line to selectively operate the switch to extend a connection.

9. In a signal system, two control offices having an interconnecting line, a plurality of sources of signalling current each source having different electrical characteristics than the other sources, devices in one of said offices, said devices responsive to a plurality of received signals for transmitting said signals over the line by means of a signal of substantially constant length including a code impulse of current from all of said sources, a receiving device at the other office responsive to said code, and means controlled by said receiving device to translate the code to signals corresponding to said received signals.

10. In a telephone system, a trunk line connecting two exchanges, a plurality of frequencies of alternating current, a plurality of automatic switches successively controlled by received impulses to select a plurality of particular combinations of said frequencies, means for successively controlling each of the switches connected to said particular frequencies to individually apply to said line a signal including a code pulse of the selected frequencies, the interval between the connection of each of the successive signals controlled by the switch that applied the preceding code, a device responsive to said code signals, other automatic switches, and means controlled by said responsive device to operate said other switches by pulses corresponding to the received impulses used to operate each of said first automatic switches to select the connected frequencies.

11. In a telephone system, a toll line terminating on a device responsive to particular voice frequencies for controlling switches from received digital information, means for transmitting over said line particular digital information as a voice frequency signal of constant length comprising a preliminary portion of said voice frequencies to prepare the device on said line for the digital portion comprising a lesser number of said frequencies for operating the switches.
